UNITED STATES PATENT OFFICE.

EDWARD N. LA VEINE, OF KANSAS CITY, MISSOURI.

DESIGN FOR A RUBBER-DAM CLAMP.

SPECIFICATION forming part of Design No. 30,883, dated May 30, 1899.

Application filed May 1, 1899. Serial No. 715,243. Term of patent 7 years.

To all whom it may concern:

Be it known that I, EDWARD N. LA VEINE, of Kansas City, Jackson county, State of Missouri, have invented a new and original Design for Rubber-Dam Clamps, of which the following is a full, clear, and exact description, reference being had to the accompanying drawings, forming a part thereof.

Figure 1 is a plan view of a rubber-dam clamp embodying my new design. Fig. 2 is a side elevation thereof. Fig. 3 is a transverse sectional view taken approximately on the line 3 3 of Fig. 2.

As shown in the drawings, the leading or material feature of my design consists of an elongated flat body 1, the ends 2 of which are rounded, and in the right-hand end of this body is formed a plurality of transversely arranged slots 3. Extending transversely across the top of the left-hand end of the body 1 is a semicircular rib 4, and projecting upwardly from said rib 4, at equal distances apart, are the points 5. Extending upwardly from the side edges of the center of the body 1 are the semicircular ears or projections 6,

and upon said ears 6 is the flat body 7, the left-hand end of which is rounded to correspond with the end of the body 1; but the right-hand end of said body 7 does not extend outwardly as far as the right-hand end of the body 1. The top surface of the right-hand end of the body 7 is ornamented with the radially-arranged ribs or corrugations 8, while the right-hand end of said body is ornamented with the ribs or corrugations 9. Upon the under side of the left-hand end of the body 7 is the transversely-arranged rib 10, the same resting directly upon the rib 4, and in said rib 10 is formed a plurality of apertures 11, which receive the points 5, previously mentioned.

I claim—

The design for a rubber-dam clamp, substantially as herein shown and described.

In testimony whereof I affix my signature in presence of two witnesses.

EDWARD N. LA VEINE.
